United States Patent Office

Des. 195,130

Patented Apr. 30, 1963

195,130

PREFABRICATED FENCE PANEL

John T. Hampton, 834 Lori Ave., Sunnyvale, Calif.

Filed May 7, 1962, Ser. No. 70,018

Term of patent 14 years

(Cl. D28—1)

FIG. 1.

FIG. 2.

FIG. 3.

FIGURE 1 is a front elevational view of a prefabricated fence panel, showing my new design;

FIGURE 2 is a top plan view thereof; and

FIGURE 3 is a rear elevational view of my prefabricated fence panel.

I claim:

The ornamental design for a prefabricated fence panel, substantially as shown.
